(57) **CLAIM**

The ornamental design for an adjustable paddle shaft, as shown and described.

DESCRIPTION

FIG. 1 is a perspective view of the adjustable paddle shaft of our new design from the front top; FIG. 2 is an elevational view thereof from the front; FIG. 3 is an elevational view thereof from the rear; FIG. 4 is a top plan view thereof; FIG. 5 is a bottom plan view thereof; FIG. 6 is an elevational view thereof from the right; FIG. 7 is an elevational view thereof from the left; FIG. 8 is an elevational cross-sectional view thereof from the right, taken along line 8-8 in FIG. 4; FIG. 9 is a perspective view thereof from the front right; and, FIG. 10 is an exploded perspective cross-sectional view thereof from the front right. The broken lines illustrated show portions of the adjustable paddle shaft that form no part of the claimed design.
